UNITED STATES PATENT OFFICE.

CARL SCHRAUBSTADTER, JR., OF ST. LOUIS, MISSOURI.

DESIGN FOR A FONT OF PRINTING-TYPE.

SPECIFICATION forming part of Design No. 24,807, dated October 29, 1895.

Application filed September 27, 1895. Serial No. 563,917. Term of patent 14 years.

To all whom it may concern:

Be it known that I, CARL SCHRAUBSTADTER, Jr., a citizen of the United States, residing at St. Louis, in the State of Missouri, have invented and produced a new and useful Design for a Font of Printing-Type, of which the following is a specification, reference being had to the accompanying drawing, showing a part thereof.

10 The drawing shows a face view of a font of type comprising upper and lower cases.

The leading features of my design consist in having light hair-lines and exceedingly heavy main lines, and in place of the ceriphs, which ordinarily extend in a horizontal direction at the top and bottom corners of the heavy vertical lines, I use a small wedge-shaped hair-line at the junction of the horizontal and vertical boundaries of these main lines, 20 this hair-line extending at an angle of forty-five degrees from both of these boundaries. This feature is also adopted in some of the heavy letters and letters having straight lines not vertical, as capitals G, K, M, N, V, 25 W, X, Y, and Z, lower-case v, w, x, and y, and in the punctuation-marks, which are rectilinear instead of round. Such parts of the letters as are ordinarily crescent-shaped, being convex on the outside of the letter and 30 concave on the inside, have the outer contour of the usual shape, while the inner contour is a compound curve, giving the surface a tear-shaped appearance. This is exemplified in capitals B C D G O P Q R, figures 3 5 6 8 9

35 0 ? &, and lower-case a, b, c, d, e, g, o, p, and q. The ceriphs in some of the letters, instead of being confined within the space outlined by the top and bottom lines of the letter, extend beyond it the same distance as on the other 40 side. This is shown at the top and bottom of capital E, top of capital F, bottom of capital

L, top of capital T, top and bottom of capital Z, cross-line of figure 4, cross-line of lower-case f and t, and top and bottom of lower-case z. The cross-line and top of capital A each 45 consist of compound-curved lines, as does also the cross-line of capital H. The center and bottom line of second capital E, top line of second capital F, and bottom of second capital L are also compound-curved lines, but heavier 50 on the ends farthest removed from the main line of the letter. In addition to the small hair-lines the hair-lines on capitals A K N U V W X Y and lower-case k, v, x, and y end in triangles, at the ends of the extreme corners of 55 which the fine hair-lines first referred to are placed. The dots on the lower-case i and j, instead of being round or square, as is usually the case, are triangular. There is also provided, in addition to the square one, a triangular 60 period. Other letters, in which the hair-lines ordinarily end in a round or oval-shaped ball, have these balls hollowed out on the inside, while the outside remains convex, as shown in capital J, figures 2 3 5 ?, and 65 lower-case f, j, r, and y. Other letters which ordinarily have ceriphs at these points are equipped with an appendix similar to these last-named characters, as the capitals C and S.

Certain of the lower-case letters have their 70 upper curved contours extending slightly beyond the main line and joined to it by small ceriphs. These are the h, m, and n, and the same thing applies to lower contours of the t and n.

75 What I claim is—

The design for a font of printing type as herein shown and described.

CARL SCHRAUBSTADTER, JR.
